Filed Nov. 21, 1969, Ser. No. 20,213

Term of patent 14 years

Int. Cl. D26—04

U.S. Cl. D48—24

Fig. 1

Fig. 2

Fig. 3

FIG. 1 is a perspective view of the combined portable light or similar article and power pack therefor embodying my new design;

FIG. 2 is a view thereof showing the top of the power pack and one end of the portable light;

FIG. 3 is a view thereof showing one end of the power pack and the side of the portable light.

The undisclosed side of the portable light is identical to the side shown in FIGS. 1 and 3. The end of the portable light opposite to that shown in FIG. 2 is flat and plain. The electric cord is broken away in FIGS. 1, 2 and 3 to indicate indeterminate length.

I claim:

The ornamental design for a combined portable light or similar article and power pack therefor, as shown and described.
